UNITED STATES PATENT OFFICE

SAMUEL SUMMER, OF ALBANY, NEW YORK, ASSIGNOR OF ONE-HALF TO FRANK S. SUMMER, OF NEW YORK, N. Y.

FOUNTAIN PEN

Application filed August 9, 1929. Serial No. 384,660.

My present invention relates to a fountain pen and more particularly to a fountain pen of that type commonly known as a self-filling pen. In this type of pen, as generally constructed, the barrel contains a rubber sack or receptacle which in filling the pen is evacuated by being compressed by a lever, or otherwise, in order that when the end of the pen is dipped into an ink or writing fluid and the lever released the sack is filled by the action of atmospheric pressure.

It is more or less common experience in the use of fountain pens to find the pen point, and oftentimes the feed tube, clogged because of the ink or writing fluid having become dried therein after a period of non-use. Furthermore, much inconvenience, and sometimes difficulty, is experienced in causing the ink to flow properly. The usual method of inducing the ink to flow is by shaking or knocking the pen against some other object. Now the purpose of my present invention is to overcome this difficulty and in a fountain pen preferably of the self-filling type to provide a means for flushing or priming the feed tube and pen point whereby the ink or other writing fluid will flow sufficiently freely for writing purposes whenever it is desired to use the pen. Of course, the flushing of the feed tube and pen point might be accomplished by actuating the filling lever, but when thus flushing the pen point the ink is likely to be ejected too freely from the pen and possibly with sufficient force to not only squirt the ink and consequently waste the same, but in addition to soil the objects with which the ink thus wasted comes into contact. It is the purpose of my invention to so incorporate the flushing and priming devices that in the ordinary use of the pen they are operated automatically, that is, unconsciously by the writer although, of course, they may be otherwise operated at the convenience of the user. For example, in carrying out the invention the priming of the feed tube and the pen point may be effected by placing the cap on the reverse end of the pen barrel, or by removing the cap from its normal non-use position on the pen barrel, or removing the pen from its socket in the case of a desk type of

fountain pen. This action is accomplished by the employment of a suitable device to compress the ink sack or container only sufficiently to cause enough ink to flow into the feed tube and to the pen point to supply the necessary initial amount of ink for writing purposes. This apparatus has a further advantage that when either removing the cap from the reverse end of the barrel, or when placing the cap over the pen point on the barrel, there is a tendency to permit the ink sack or reservoir to expand slightly thereby causing the ink to flow from the pen point and feed tube into the sack to thus tend, at least, to keep the feed tube and pen point clean when not in use and thereby prevent the drying of the ink therein and consequently obviating the usual dried ink deposits which ordinarily prevent the ink from flowing to the pen point.

The fountain pen made in accordance with my invention will be hereinafter more particularly described in conjunction with the accompanying drawings in which Figure 1 is a plan of a fountain pen in which the invention is incorporated,

Fig. 2 is an enlarged section on line 2—2, Fig. 1,

Fig. 3 is an enlarged partial longitudinal section illustrating the form of the invention as shown in Figs. 1 and 2,

Fig. 4 is a section on line 4—4, Fig. 3,

Fig. 5 is a view similar to Fig. 1 showing another form of the invention,

Fig. 6 is a partial longitudinal section showing the form of the invention as illustrated in Fig. 5.

Referring to the drawings and more particularly to Figs. 1 to 4 inclusive it will be seen that in carrying out the invention the pen made in accordance therewith is constructed to include the usual barrel 15 having a feed tube section 16 at one end thereof and in which there is fitted a pen point 17. The pen is made to include the usual cap or cover member 18. Also, as is customary, the end of the barrel adjacent the feed tube section 16 may be screw threaded, as indicated at 19, in order to be engaged by the internal screw 100

threads 20 provided for this purpose within the cap 18.

Of course, as in some instances, these screw threads may be omitted and the cap held frictionally in position to cover the pen point in the same manner that when the pen is in use the cap is placed over and maintained frictionally on the reverse end of the barrel.

In this type of pen the barrel 15 is fitted 10 with a sack or reservoir 21 made of suitable material such, for example, as rubber and adapted to contain ink or other writing fluid. One end of the sack 21 is suitably connected to the feed tube section 16 and these parts secured in the barrel in the usual or any desired manner. In a suitable position in the barrel 15 the same is fitted with a lever 22 adapted to be operated to compress the adjacent portion of the sack, thereby evacuating the same 20 so that after the pen point and the end of the feed tube have been placed beneath the surface of a quantity of writing fluid and the lever released the ink will be drawn into the sack or reservoir to substantially fill the same 25 until depleted by use. Still furthermore, and as is also customary, the cap 18 may be provided with a suitable clip indicated at 23 made in any of the usual manners for maintaining the pen in a position in the pocket by 30 passing the edge of the pocket between the clip and the adjacent portion of the cap.

The parts of the pen to which reference has hereinbefore been made are the most usual constructions and the invention in the present 35 case relates more particularly to a button or plunger associated with the barrel and adapted when pressed inwardly to depress the sack or reservoir, or a portion thereof, sufficiently to cause enough ink or other writing fluid to 40 flow to the feed tube section and the pen point to prime the same.

To this end, as illustrated in these figures of the drawing, I may employ a plate 24 of sufficient dimensions to accomplish the purpose 45 and provide the same with a flange 25 which extends through a slot 26 provided therefor in the pen barrel 15. A plate 24 normally lies between a portion of the sack 21 and the inner face of the pen barrel, the resiliency of the 50 sack being sufficient to normally maintain the outer surface of the plate against the inner face of the pen barrel with the flange 25 protruding through and extending beyond the slot 26. These parts, namely the plate 55 24 and the flange 25, therefore, comprise a depressible button which, as illustrated in these figures of the drawing, is located adjacent the end of the barrel opposite the feed tube and the pen point end. It will now be readily 60 understood that when the cap 18 is removed from this type of pen to uncover the pen point and is placed over the opposite end of the barrel, as shown in Figs. 3 and 4, it will 65 depress the flange 25 of the button, causing the plate 24 thereof to move inwardly and

compress the adjacent end of the ink sack 21. The parts are so designed, as will furthermore be understood, that by thus compressing the ink sack sufficient ink is caused to flow to the feed tube and pen point to adequately prime the same. It will also be understood that in removing the cap from this end of the barrel the resiliency of the sack, together with the 70 contents thereof, is normally sufficient to return the button to its initial position in which the plate lies against the inner face of the barrel and the flange extends beyond the same, as clearly illustrated in Fig. 2, thereby causing a slight expansion of the sack and a resultant flow of ink from the feed tube and pen point into the sack, this action obviously tending to keep the pen point and the passage or passages through the feed tube clean.

In the form of the invention as illustrated in Figs. 5 and 6 it will be seen that I may 75 employ a plate 27 connected exteriorly or otherwise to the barrel and in any suitable position by means of rivets 28 or other means. This plate has connected thereto a spring arm 29 which extends through an 80 opening 30 provided therefor in the wall of the barrel 15 of the pen. Lying within the barrel and between the same and the adjacent portion of the ink sack 21 there is a lever which is connected to the end of the 85 spring arm in any suitable manner. One end of this lever is indicated at 31 and the opposite end at 32. The end 32 of the lever is extended to provide a flange or button 33 that 90 normally projects through and beyond a slot 34 provided in the wall of the pen barrel for this purpose. These parts are so constructed that when the cap covers the feed tube and pen point, or when a socket covers these 95 parts in the case of a desk fountain pen, the end of the cap or socket engages the flange 100 33 thereby depressing the same and moving the lever arm 31 to the position shown in the dotted lines in Fig. 6, this action, of course, permitting the adjacent portion of the sack 105 to expand to thereby draw ink from the feed tube section of the pen point into the sack, it being understood that in the case of a desk pen the socket into which the pen fits is the equivalent of the usual cap.

Obviously also when the cap is removed or the pen removed from the socket the action of the spring 29 moves the lever arm 31 inwardly against the adjacent portion of the sack 21 and sufficiently far only to cause 110 enough ink to flow through the feed tube section 16 to the pen point to prime the same. When in this position the flange 33 or button projects beyond the surface of the barrel so as to be depressible when the cap or socket 115 is again placed in position to cover the feed tube section and pen point.

It will furthermore be understood that the various types of constructions as herein 120 illustrated and described are now considered 125 130

to be the best forms of the invention but that other and equivalent constructions may be employed without departing from the nature and spirit of the invention.

5 I claim as my invention:—

1. In a self-filling fountain pen, a barrel, a feed tube section, a sack secured to the feed tube section and lying within the barrel, a pen point secured in the feed tube section, a 10 cap normally adapted to cover the feed tube section and pen point and to be fitted on the opposite end of the barrel, and a button extending through the barrel and adapted to be operated by the said cap to cooperate with 15 the said sack in the normal use of the pen to force only sufficient writing fluid to the pen point to prime the same.

2. In a self-filling fountain pen, a barrel, a feed tube section, a sack connected to the feed tube section and lying within the barrel, a pen point, a cap adapted normally to cover the feed tube section and pen point, and mechanical means operative upon the removal of the cap for compressing the sack to 25 force a sufficient quantity of writing fluid therefrom to the pen point to prime the same.

3. In a self-filling fountain pen, a barrel, a feed tube section, a sack connected to the feed tube section and lying within the barrel, a pen point, a cap adapted normally to cover the feed tube section and pen point, a yieldingly mounted lever normally maintained in an initial position by the cap when in place to cover the feed tube section and pen point 35 and adapted upon the removal of the cap to compress the sack to force a sufficient quantity of writing fluid therefrom to the pen point to prime the same.

4. In a self-filling fountain pen, a barrel, a feed tube section, a sack connected to the feed tube section and lying within the barrel, a pen point, a cap adapted normally to cover the feed tube section and pen point, a spring member attached to the barrel, and a lever 45 secured to the said spring and having an arm extending through a slot provided therefor in the barrel to be engaged by the cap when the same is in position to cover the feed tube section and pen point and to be operative 50 when the cap is removed to compress the sack to thereby force a sufficient quantity of writing fluid therefrom to the said feed tube section and pen point to prime the same.

5. In a self-filling fountain pen, a barrel, a feed tube section, a sack connected to the feed tube section and lying within the barrel, a pen point, a cover adapted to receive the feed tube section and pen point, a yieldingly mounted lever normally maintained in an initial position by the said cover when the feed tube section and pen point are within the same and adapted upon the removal of the feed tube section and pen point to compress the sack to force a sufficient quantity

of writing fluid therefrom to the pen point to prime the same.

6. In a self-filling fountain pen, a barrel, a feed tube section, a sack connected to the feed tube section and lying within the barrel, a pen point, a cover adapted to receive the feed tube section and pen point, a spring attached to the barrel, and a lever secured to the spring having an arm extending through a slot provided therefor in the barrel, the lever adapted to be disengaged from the said cover when the feed tube section and pen point are removed therefrom whereby the lever may compress the sack to thereby force a sufficient quantity of writing fluid from the sack to the feed tube section and pen point for priming the same.

7. In a self filling fountain pen, a cap, a barrel, a feed tube section, a pen point, a sack extending from the pen point section and lying within the barrel, and a button having a part lying between the said sack and the barrel and another part extending through the circumference of the barrel to be automatically operative in the use of the pen by placing the cap on the barrel thereby depressing the sack to force only sufficient writing fluid to the pen point to prime the same.

8. In a self filling fountain pen, a cap, a barrel, a feed tube section, a pen point, a sack extending from the pen point section and lying within the barrel, and a button having a part lying between the said sack and the barrel and another part extending through the circumference of the barrel to be automatically operative in the use of the pen by placing the cap on the end of the barrel thereby depressing the sack to force only sufficient writing fluid to the pen point to prime the same, the movement of the said button being determined by its projecting surface beyond the outer surface of the circumference of the barrel.

9. In a self filling fountain pen, a cap, a barrel, a feed tube section, a pen point, a sack within the barrel for containing the writing fluid, and means automatically operative to withdraw the writing fluid from the pen point after the pen has been used.

10. In a self filling fountain pen, a barrel, a feed tube section, a sack connected to the feed tube section and lying within the barrel, a pen point, a cap adapted to position on the end of the barrel during the normal operation of the pen, mechanical means operative upon placing the cap over the pen point and feed tube section to permit the sack to expand thereby withdrawing the writing fluid from the pen point into the same.

Signed by me this 30th day of July, 1929. 125
SAMUEL SUMMER.
